DESIGN FOR A SHOE

Jerome Edson Andrews, Andover, Mass.

Application November 19, 1936, Serial No. 66,026

Term of patent 3½ years

To all whom it may concern:

Be it known that I, Jerome Edson Andrews, a citizen of the United States, residing at Andover, in the county of Essex and Commonwealth of Massachusetts, have invented a new, original, and ornamental Design for a Shoe, of which the following is a specification, reference being had to the accompanying drawing, forming a part thereof, in which

The figure is a view in perspective of a shoe showing my new design, the outline of the shoe being shown conventionally in dotted lines.

The dominant feature of my invention resides in the tongue shown in full lines.

I claim:

The ornamental design for a shoe substantially as shown and described.

J. EDSON ANDREWS.
